Attorney

C. H. Parker

UNITED STATES PATENT OFFICE.

WILLIAM H. McCRARY, OF NORFOLK, VIRGINIA, ASSIGNOR TO McCRARY SANITARY COLLAPSIBLE BARREL COMPANY, INCORPORATED, OF PHILADELPHIA, PENNSYLVANIA, A CORPORATION OF DELAWARE.

COLLAPSIBLE BARREL

1,391,900.

Specification of Letters Patent. Patented Sept. 27, 1921.

Application filed May 10, 1921. Serial No. 468,319.

To all whom it may concern:

Be it known that I, WILLIAM H. McCRARY, a citizen of the United States, residing at Norfolk, in the county of Norfolk and State 5 of Virginia, have invented certain new and useful Improvements in Collapsible Barrels, of which the following is a specification.

This invention relates to collapsible barrels, and more particularly to a barrel 10 formed of sections having interlocking joints.

An important object of the present invention is the provision of a collapsible barrel 15 which will be durable and of substantially the same strength as a barrel of permanent construction.

A further object is the provision of a barrel 20 having hooped sections mounted on the barrel sections and means for locking the adjoining ends of the hooped sections to each other.

In one form of the invention, the hoop 25 sections are substantially cylindrical in shape and one end of each section is provided with a projecting lip or tongue having a threaded block or nut arranged therein. This lip or tongue is adapted to enter the end of the adjacent section and a screw 30 or other fastening element is passed through an opening in the end of the adjacent section and received in the threaded block.

In the accompanying drawings, I have 35 shown one embodiment of the invention. In this showing:

Figure 1 is a side elevation,

Fig. 2 is a horizontal sectional view on line 2—2 of Fig. 1,

Fig. 3 is a vertical sectional view on line 40 3—3 of Fig. 2,

Fig. 4 is a horizontal sectional view on line 4—4 of Fig. 1,

Fig. 5 is a detail elevation showing one 45 of the ends of the hoop section,

Fig. 6 is a sectional view on line 6—6 of Fig. 5,

Fig. 7 is a detail view of the blank from 50 which the hoop section is formed,

Fig. 8 is an end elevation of the hoop section detached, and,

Fig. 9 is a vertical sectional view similar 55 to Fig. 8, taken at right angles thereto.

Referring to the drawings, the reference 60 numeral 1 designates the stave sections of

the barrel. As shown, a pair of substantially semi-cylindrical stave sections are employed. The use of a particular number of stave sections, however, forms no part of the invention and a larger number of stave sections may be employed and connected to each other in the manner to be described. 55

The opposite sides of the stave sections are provided with male and female sections adapted to engage corresponding female and male connections formed on the adjacent 60 stave sections of the barrel. As shown, the male section comprises a plate arranged over the edge of the stave section, as at 3, the plate being extended along the sides of the stave section, as at 4. The female connection comprises a plate, portions of which are arranged along the sides of the stave sections, as indicated at 5. At one side of the barrel, the plate is extended outwardly and then returned toward the edge of the 65 barrel forming a side wall 6 of the groove. The adjacent portion of the plate is arranged along the edge of the stave section, as indicated at 7, and the plate is then extended outwardly parallel to the wall section 70 6, as shown at 8. This provides a groove for the reception of the male connection carried by the adjacent stave edge. As shown, one of the walls of the groove is offset, as at 9, a sufficient distance to allow 75 for the width of the male connection. 80

Each of the stave sections is provided with a plurality of hoop sections 10. Any number of hoop sections may be employed, depending upon the size of the barrel and the purpose for which it is to be used. As shown, the hoop sections are substantially semi-cylindrical and are provided with longitudinal flanges 11 by means of which the hoop section is secured to the stave section 95 of the barrel. The opposite ends of the hoop sections are provided with male and female connections adapted to engage corresponding female and male connections of the adjoining sections. In forming the male 100 connection (see Fig. 7), the hoop sections is provided with a projecting tab 12 and a pair of slots 13 are cut transversely through the flanges a sufficient distance from the end of the hoop section. An opening 14 is 105 formed adjacent the end of the hoop section and a threaded block or nut 15 is arranged beneath this opening. The block is adapted

to be arranged on the tab 12, which is bent upon itself, as indicated at 16, and then extended beneath the body portion of the hoop section as shown in Figs. 4 to 6. The portion 17 of the flanges between the slots 13 and the end of the hoop section are then bent or extended under the body portion, the inner end adjacent the slots being offset as at 18, to prevent displacement of the block 15. The entire end of the hoop section is then compressed or reduced in size to form a lip 19 sufficiently small to be received in the female end of the adjacent hoop section. The female end of the hoop section is provided with an opening adapted to register with the opening 14 and the threaded opening in the block 15 for the reception of a bolt or set screw 20.

The heads of the barrel are preferably formed of sheet metal or similar material and consist of substantially circular portions 21, the ends of which are provided with substantially channel-shaped sections 22 for the reception of the ends of the stave sections. Bolts 23 are passed through these channel sections and through openings in the stave sections and these bolts are adapted to receive nuts 24 to secure the heads in position.

A strip 25 is arranged longitudinally of the stave sections between the ends of the stave section. The ends of the strip are extended over the ends of the stave sections, as at 26, and then extended along the outside of the stave sections as indicated at 27. The extended ends of the strip 25 are adapted to be arranged beneath the head of the barrel when the head is in position and the extension 27 terminates at substantially the bottom of the outside of the head. Suitable fastening elements 28 may be passed through the head, the strip 25 and the stave section. The hoop sections may be bolted or riveted to the strip 25, as indicated at 29.

It will be apparent that by means of the present construction, a barrel is provided which may be readily and quickly assembled and which is of substantial strength sufficient to meet the requirements. The barrel may be knocked down when shipped empty, and thus effect a saving of space.

The interlocking hoop connections which are positively retained in position by means of screws 20, prevent the stave sections from separating, as the hoop sections are secured directly to the corresponding stave sections.

It is to be understood that the form of my invention herewith shown and described is

to be taken as a preferred example of the same, and that various changes in the shape, size, and arrangement of parts may be resorted to without departing from the spirit of the invention or the scope of the subjoined claims.

Having thus described my invention, I claim:

1. A collapsible barrel comprising a plurality of stave sections, the adjacent edges of said stave sections being provided with interlocking joints, hoop sections secured to said stave sections, one end of each of said hoop sections being provided with a recess, a projecting lip arranged on the other end of each of the hoop sections and adapted to be received in the recess of the adjacent section, and fastening means to retain said hoop sections in position.

2. A collapsible barrel comprising a plurality of stave sections, the adjacent edges of said stave sections being provided with interlocking joints, hoop sections secured to said stave sections, one end of each of said hoop sections having a projecting lip arranged thereon, said projecting lip being adapted to be received within the end of the adjacent hoop section, a threaded block mounted in said lip, and securing means passing through the adjacent hoop section and entering said block.

3. A collapsible barrel comprising a plurality of stave sections, the adjacent edges of said stave sections being provided with interlocking joints, hoop sections secured to said stave sections, a portion of each of said hoop sections being spaced from the stave section, one end of each of said hoop sections being provided with a pair of transverse slots in alignment with each other, the portion of the hoop section between the slots and the end being arranged beneath the spaced portion, a threaded block arranged beneath the spaced portion and retained in position by said portions, the opposite end of each of the hoop sections being adapted to receive said first mentioned end and being provided with an opening adapted to register with said threaded block, and a fastening element passing through said opening and being received in said block.

In testimony whereof I affix my signature in presence of two witnesses.

WILLIAM H. McCRARY.
